FIG. 3.

FIG. 4.

FIG. 5.

FIG. 8.

FIG. 9.

FIG. 10.

FIGURE 1 is a perspective view of a cigarette lighter embodying the present design;

FIGURE 2 is a side elevational view thereof, as viewed from the lower-right in FIGURE 1;

FIGURE 3 is a side elevation as viewed from the upper-right in FIGURE 1;

FIGURE 4 is a top plan view of the cigarette lighter; FIGURE 5 is a bottom plan view thereof;

FIGURE 6 is a perspective view of a second embodiment of the cigarette lighter;

FIGURE 7 is a side elevational view of such second embodiment, as viewed from the lower-right in FIGURE 6;

FIGURE 8 is a side elevational view as viewed from the upper-right in FIGURE 6;

FIGURE 9 is a top plan view of the second embodiment; and

FIGURE 10 is a bottom plan view thereof.

Except for the letters and the three legs connected thereto, the side not shown in FIGURE 2 is identical to the side shown therein. Except for the letters, the sides

not shown in FIGURES 3, 7 and 8 are, respectively, identical to the sides shown in such figures.

The characteristic features of my design reside in the configuration of the lighter housing and stem which terminates in letter supports.

I claim:

The ornamental design for a cigarette lighter, substantially as shown and described.
